[57] CLAIM

The ornamental design for a physical exercise frame, as shown and described.

DESCRIPTION

FIG. 1 is a front perspective view of a physical exercise frame showing my new design;

FIG. 2 is a side elevational view thereof, the side opposite being a mirror image;

FIG. 3 is an end elevational view thereof;

FIG. 4 is an end elevational view of the end opposite that shown in FIG. 3;

FIG. 5 is a top plan view thereof;

FIG. 6 is a side elevational view thereof with the broken lines representing a human figure as environment;

FIG. 7 is another side elevational view thereof with the broken lines representing a human figure as environment; and,

FIG. 8 is another side elevational view thereof showing the adjustable rest member in an alternate position.
